UNITED STATES PATENT OFFICE

JOHN G. CALLAN, OF LYNN, MASSACHUSETTS, ASSIGNOR TO GENERAL ELECTRIC COMPANY, A CORPORATION OF NEW YORK.

MEANS FOR ATTACHING TURBINE-BUCKETS.

No. 830,878.

Specification of Letters Patent.

Patented Sept. 11, 1906.

Application filed February 23, 1906. Serial No. 302,427.

To all whom it may concern:

Be it known that I, JOHN G. CALLAN, a citizen of the United States, residing at Lynn, county of Essex, State of Massachusetts, have invented certain new and useful Improvements in Means for Attaching Turbine-Buckets, of which the following is a specification.

The present invention relates to means for attaching buckets of elastic-fluid turbines to their support, and has for its object to provide an improved arrangement whereby the buckets are securely fastened in place or are readily removed when for any reason it becomes necessary or desirable.

In the accompanying drawings is illustrated embodiments of the invention, Figure 1 being a partial view in elevation of a bucket-carrying element. Fig. 2 is a slightly-modified form, showing buckets mounted upon the inside of a cylinder or drum. Fig. 3 is a cross-section through the bucket-base and securing means, and Fig. 4 is a similar section of a slight modification.

1 represents a bucket-carrying element. It may be stationary or rotary, as desired. The buckets may be mounted on the periphery, as shown in Fig. 1, or on the inside, as shown in Fig. 2. The surface arranged to receive the buckets is provided with as many channels as there are rows of buckets. These channels are wider than the base 2 of the buckets and are provided with overhanging shoulders 3. These shoulders may be of any suitable shape. In Fig. 3, for example, a square shoulder is provided, and in Fig. 4 the wall 4 is inclined from the bottom to the top, thus giving to the channel the form of a dovetail in cross-section.

The buckets 5 may be made in any suitable way. For example, they may be cut from solid stock, cast, or made of drawn stock cast into the base 2. The bases are made in segmental form of convenient length for manufacture. In one or both sides of the base are formed grooves 6, so arranged that a shoulder 7 is provided to receive the exposed end of the staking-piece 8. As shown in one embodiment of the invention, the staking-piece, Fig. 3, comprises a flat portion 9, that extends parallel with the bucket-base and has a projection 10, that hooks under the overhanging shoulder 3 on the support and is held thereby. The other end of the staking-

piece projects slightly beyond the surface of the support and is adapted to be bent over, as shown at 11, to engage the shoulder on the base and hold the same rigidly in place. These staking-pieces are preferably made in segmental form and are usually of a length corresponding to the length of a bucket-segment. I may, however, make them longer or shorter, as desired. By making each piece of a length corresponding to that of a bucket-segment and matching the joints it is a simple operation to assemble or remove the bucket-segments than where the staking-pieces overlap the joints of the segments.

In assembling the parts the staking-pieces are first mounted in position in a channel. Then the bucket-base is fitted into place between the staking-pieces, and finally the ends of the staking-pieces are bent over to engage the shoulders on the bucket-base and hold the same in place. These ends may be rolled into place by any suitable tool or bent over by a pneumatic hammer or equivalent device. When for any reason it becomes necessary or desirable to remove a bucket-segment, the exposed end of each staking-piece is cut off with a cold-chisel which permits the bucket-segment to be readily removed. In reassembling the parts new staking-pieces are provided.

In Fig. 4 is shown a slight modification wherein the bucket-base-receiving channel in the support is made of dovetail shape in cross-section as distinguished from the square shoulder shown in Fig. 3. The body portion 9 of each staking-piece is thicker at the base than at the exposed end 8, so that when the latter is bent over any tendency for the bucket-base to pull out tends to wedge the staking-pieces more firmly against the side walls of the groove. It will be seen that in both cases the walls of the channel overhang sufficiently to hold the staking-pieces against radial strains. The remarks about assembling and taking down the structure shown in Fig. 3 apply to the structure shown in Fig. 4.

In Fig. 1 I have shown the buckets provided with a cover 12, made up in segments of suitable length and secured by tenons 13, formed integral with the ends of the buckets. These covers may, however, be omitted, if desired.

In Fig. 2 the buckets are shown inside of a

drum or other support 1, and the ends of the buckets opposite to the base are uncovered.

My invention is applicable to turbines of the jet type, and also to machines of the reaction and other types.

In accordance with the provisions of the patent statutes I have described the principle of operation of my invention, together with the apparatus which I now consider to represent the best embodiment thereof; but I desire to have it understood that the apparatus shown is only illustrative and that the invention can be carried out by other means.

What I claim as new, and desire to secure, by Letters Patent of the United States, is—

1. In an elastic-fluid turbine, the combination of a support having one or more channels, a bucket-carrying base mounted in the channel, and staking-pieces situated between the bucket-base and the walls of the channel, said staking-pieces being held by the walls of the groove and turned over at their outer ends to secure the buckets.

2. In an elastic-fluid turbine, the combination of a support provided with one or more channels having overhanging shoulders

on opposite sides, a bucket-carrying segmental base mounted in the channel and provided with shoulders on opposite sides, and staking-pieces located between the sides of the channel and the bucket-base, the inner ends of the staking-pieces being held in place by the support and the outer ends turned over to engage the said shoulders.

3. In an elastic-fluid turbine, the combination of a support having a channel formed therein with an overhanging wall, a bucket-carrying base mounted therein and provided with a shoulder on one side, and a staking-piece located between the wall of the channel and the bucket-base and secured at its inner end by the overhanging wall of the channel, the outer end being bent over to engage the shoulder on the bucket-base and secure it in place.

In witness whereof I have hereunto set my hand this 20th day of February, 1906.

JOHN G. CALLAN.
